UNITED STATES PATENT OFFICE.

VAN BUREN FOSTER, OF BOYLES, ALABAMA.

JOURNAL-BOX.

1,224,730.

Specification of Letters Patent.

Patented May 1, 1917.

Application filed January 30, 1917. Serial No. 145,436.

To all whom it may concern:

Be it known that I, VAN B. FOSTER, a citizen of the United States, residing at Boyles, in the county of Jefferson and State of Alabama, have invented new and useful Improvements in Journal-Boxes, of which the following is a specification.

This invention relates to improvements in journal boxes, and has particular application to a journal box of that type employing anti-friction rollers in place of the usual brasses.

In carrying out the present invention, it is my purpose to provide a journal box of the class described wherein the anti-friction rollers will be held in proper positions around the journal, and wherein the rollers may be readily removed from the journal box whenever it is desired to clean or repair the bearing.

It is also my purpose to provide a journal box of the type set forth wherein friction will be reduced to a minimum and the need of brasses and oil saturated waste will be eliminated.

With the above and other objects in view, the invention consists in the construction, combination and arrangement of parts hereinafter set forth and falling within the scope of the claims.

In the accompanying drawings:—

Figure 1 is a longitudinal sectional view through a journal box constructed in accordance with the present invention.

Fig. 2 is a cross sectional view on the line 2—2 of Fig. 1.

Fig. 3 is a similar view on the line 3—3 of Fig. 1.

Fig. 4 is an enlarged fragmentary cross sectional view showing the mounting of the cover.

Referring now to the drawings in detail, 1 designates a box having the outer end open and the inner end closed by a wall formed centrally with an opening 2. Integral with the top of the box 1 adjacent to the outer end thereof are upwardly projecting ears 3, the purpose of which will be presently described. Extending through the opening 2 in the rear wall of the box 1 and projecting into the box is a journal 4, and the outer end of the journal terminates short of the outer end of the box. The journal 4, as usual, is of less diameter than the axle, and this reduced diameter forms a shoulder 5 at a point contiguous to the inner surface of

the rear wall of the box, while formed on the outer end of the journal is an annular flange 6 that coacts with the shoulder 5. At a point between the shoulder 5 and the outer surface 60 of the rear wall of the journal box the diameter of the journal is stepped up, but is less than the diameter of the axle, and formed in the inner end wall of the box is a vertical slide way 7 that opens onto the bottom of 65 the box. Mounted in this slide way surrounding the journal is a dust guard 8. Arranged within the box 1 around the journal 4 are bearing rollers 9 extending longitudinally of the journal and confined between 70 the flange 6 and the shoulder 5. Mounted against the under surface of the top wall of the box is a wedge 10 having the lower side concaved in cross section to conform to the curvature of the circle described by the 75 rollers 9, and forming a bearing for the rollers at the upper side of the journal. This wedge 10 is formed with a forwardly projecting lip 11 and formed in the opposite side walls of the box in line with each other 80 and with the lip 11 are openings 12. Passed through the openings 12 is a key 13 having one end formed with a head to abut the side wall of the box and the other end formed with a transverse aperture 14 to receive a 85 cotter pin 15, whereby accidental removal of the key from the box is prevented. The upper edge of the key 13 engages the under side of the lip 11 and acts to support the forward end of the wedge, the remaining 90 portion of the wedge resting upon the rollers on the under side of the journal and acting to prevent contact between such rollers and the top wall of the box.

The forward end of the journal box is 95 closed by a cover 16, and the upper edge of the cover 16 is formed with a sleeve 17 arranged between the ears 3 and in axial alignment with openings formed in such ears, and passed through these openings is a pivot 100 bolt 18. Surrounding the pivot bolt 18 are toothed collars 19 arranged within the respective ends of the sleeve 17 and having the teeth thereon adapted to engage in notches 20 formed in the inner sides of the ears 3. 105 An expansion spring 21 surrounds the bolt 18 and has the ends thereof bearing against the collars 19 so as to force the teeth thereon into the depressions in the ears. These depressions and teeth are so arranged as to 110 interlock when the cover is in closed position and when the cover is in open position,

thereby maintaining the cover in either of its positions.

From the foregoing description taken in connection with the accompanying drawings, 5 it will be seen that I have provided a journal box wherein brasses, oil saturated waste and the like are avoided, and wherein friction between the journal and its bearing is reduced to a minimum.

10 While I have herein shown and described the preferred form of my invention by way of illustration, I wish it to be understood that I do not limit or confine myself to the precise details of construction herein described and delineated, as modification and variation may be made within the scope of the claims and without departing from the spirit of the invention.

I claim:—

- 20 1. A journal box having one end open and the other end formed with an opening through which the journal may pass into the box, rollers within the box around the journal therein, a wedge mounted in the upper end of the box and having the lower side concaved in cross section to conform to the curvature of the circle described by said rollers, a lip on the forward end of said wedge, the side of said box being formed with alining openings contiguous to said lip, and a key passing through said openings and engaging said lip to support the forward end portion of said wedge.
- 25 2. A journal box having one end open and the other end formed with an opening

through which the journal may pass into the box, rollers within the box around the journal therein, a wedge mounted in the upper end of the box and having the lower side concaved in cross section to conform to the curvature of the circle described by said rollers, a lip on the forward end of said wedge, the side of said box being formed with alining openings contiguous to said lip, a headed key passing through said openings and engaging said lip to support the forward end portion of said wedge, means for holding said key in operative position, and a cover closing the forward end of said box.

3. A journal box having one end open and the other end formed with an opening through which the journal may pass into the box, rollers within the box around the journal therein, a wedge mounted in the upper end of the box and having the lower side concaved in cross section to conform to the curvature of the circle described by said rollers, a lip on the forward end of said wedge, the side of said box being formed with alining openings contiguous to said lip, a headed key passing through said openings and engaging said lip to support the forward end portion of said wedge, said key having a slot adjacent its free end, a pin passed through said slot for holding the key in operative position, and a cover closing the forward end of said box.

In testimony whereof I affix my signature.

VAN BUREN FOSTER.
